UNITED STATES PATENT OFFICE.

WEBSTER C. ESTES, OF FLATBUSH, NEW YORK.

DESIGN FOR A BOX.

SPECIFICATION forming part of Design No. 19,457, dated December 3, 1889.

Application filed October 28, 1889. Serial No. 328,473. Term of patent 7 years.

To all whom it may concern:

Be it known that I, WEBSTER C. ESTES, a citizen of the United States, residing at Flatbush, in the county of Kings and State of New York, have invented and produced a new and original Design for a Wooden Box, of which the following is a specification.

In the accompanying drawings, Figure 1 is a vertical section showing my design, and Fig. 2 is a plan view.

The leading feature of the design of this box is the exterior shape and configuration.

The box is round, and the cover A has a

compound curved configuration sectionally at 2 3, an annular rib at 4, and a circular top 15 ornament 5.

The bottom B of the box is round and tapers downwardly, as shown.

I claim—

The design for a box, substantially as described and shown.

Signed by me this 23d day of October, 1889.

WEBSTER C. ESTES.
